COUPLER OPERATING DEVICE

Edward S. Cisco, Highland, Ind., assignor to Stanray Corporation, Chicago, Ill., a corporation of Delaware
Filed Dec. 10, 1962, Ser. No. 243,977
10 Claims. (Cl. 213—166)

This invention relates to railway car coupler operating mechanisms. More specifically the invention relates to a particular type of operating lever for operating the coupler upon rotation of the lever in a counter-clockwise direction, and to a bracket for rotatably supporting the outer end of the operating lever for convenient manipulation by a trainman from the side of the car.

This application is a continuation-in-part of my copending application Serial No. 65,692 filed October 28, 1960, now abandoned.

Due to loss and damage to lading carried by railroads, which loss has been steadily increasing, ways and means of reducing the same have been studied. A good deal of the damage comes from shocks to the car, and accordingly there has been developed a sliding center sill underframe with a cushioning arrangement for railway cars which would have little or no recoil and which would allow a considerable amount of travel of the sliding sill at all impact speeds, thereby to better protect the commodities carried within the car.

Damage to lading is the result of too rapid acceleration and deceleration of the car in which the lading is carried. To reduce the effects of too rapid acceleration and deceleration of the car, greater distance and time to effect the change in velocity are required. This necessitated the use of a sliding center sill with a cushioning device therein.

Couplers installed in this type of center sill arrangement have been made to move forward and backward a greater and greater distance. Whereas they would move in the ordinary draft gear arrangement some five to six inches, with the sliding center sill types the couplers have been made to move forty inches and more. This meant greater side swing of the couplers when the cars are rounding curves. There is a great tendency to build longer cars resulting in greater overhang from truck centers to couplers and therefore greater side travel is required at the coupler to negotiate railroad curves.

Specifically, the invention relates to an operating lever for a bottom operating coupler, mounted in an underframe construction having a very wide side swing and/or a cushion underframe resulting in excessive relative longitudinal movement between car body and coupler. Therefore the rod and the support must be designed to accommodate this wide side swing and long travel between car body and coupler, this being the principal object of the invention.

A further object of the present invention is to provide an operating device which will contract to about thirty-eight inches when the coupler is in extreme buff position and extend to some six feet and more to accommodate couplers installed in these newer types of sliding center sills with cushioning arrangement therein, and 15° side swing.

Another object is to construct such an operating device at a minimum of expense and yet be very efficient in operation.

Other objects and advantages of the invention will appear in the following description thereof.

Referring now to the accompanying drawings forming part of this application and wherein like reference characters indicate like parts.

The prior art discloses coupler operating devices for use with A.A.R. type E and earlier couplers, which devices are constructed of a plurality of parts for translating rotary motion from one part to the other and to the coupler rotor for operating the coupler. But in each instance it can be demonstrably proven that such devices are not operable when used with the recently developed sliding center sill with cushioned underframe having couplers with shanks varying in length from 21 1/4" to 34 1/2" and wherein the couplers themselves move outwardly from extreme buff position to approximately 46", and may swing laterally up to 15° on either side of the longitudinal center of the car to be able to negotiate any standard A.A.R. established curve. Obviously a 15° lateral swing of a coupler having a 34 1/2" shank would be a greater distance than a 15° lateral swing of a coupler having a 21 1/4" shank. So many factors enter into the best design of a coupler operating device to be applied to a given set of car conditions, that it is impossible to classify the designs on the basis of cushion travel alone. Other factors which must be considered in a given design are type of coupler, side travel of coupler, striker projection and construction, and width of car.

50 Referring now to the modification shown in FIGURES 1 to 6 inclusive, 10 indicates the end of a car to which the device is applied, and 12 indicates the striker to which the car coupler is assembled and which is attached to the center sill of the car. Since the coupler operating rod or lever is pivotally attached at one end to the lock lifter of the coupler for rotating and lifting the lock lifter to unlock the coupler, and at the other end is mounted in a bracket secured to the end of the car, it is obvious that the bracket and outer end of the rod or lever must be constructed so as to compensate for the wide swing and/or long travel of couplers mounted in cushion underframes.

55 The operating rod or lever is formed in two parts, the inner part 14, and the outer part 16. The bracket for mounting the outer part of the lever to the car is shown generally at 18. This bracket comprises an angle member having a vertical flange 20, which is riveted or otherwise secured to the end of the car. The other flange 22 is horizontally disposed, projecting outwardly normally, and the outer edge of which is inclined, diverging from the car end toward the coupler, as shown. The bracket is of substantial length so as to accommodate movement of the

60 65 70

lever portion 14 in following the sidewise and particularly the lengthwise relative movement of coupler to car body.

At either outer corner of the horizontal flange 22 is a reverse J-shaped member, each having a top horizontal flange 24 which rests flatwise against and is secured to the flange 22. At the outer end of flange 24 the members are turned downwardly providing a vertical flange 26 which terminate in upwardly facing U-bends 28 providing bearings for rotatably receiving the outer part 16 of the operating lever. It will be noted in FIGURE 1 that the bearings are mounted on a common axis which diverges from the car end toward the coupler.

In FIGURES 5 and 6 a modified form of bracket is shown, the angle comprising the flanges 20 and 22 being the same. However, the members at each corner of the horizontal flange 22 in this modification are different in that the hanger part of the bracket comprises a strap like angle member having a horizontal flange 30 and a vertical flange 32 depending from the horizontal flange. To the vertical flange is secured in any desired manner a Z-shaped strap member 34, one flange of each of which rests flatwise against and is secured to the flange 32. The other flange 36 of the Z-shaped member is in a parallel spaced vertical plane with flange 34, and the web 38 therebetween connects the two forming upwardly facing bearings to rotatably receive the operating rod. In either modification of bearings, they must be spaced about 34" apart so that the operating rod may extend to the required six feet.

The outer end 16 of the operating rod comprises a depending handle portion 40, and a hairpin shaped portion consisting of two spaced parallel horizontally disposed portions 42 and 44 connected by a U-bend 46. The free end terminates at the handle portion to which it is secured by welding or the like. Either horizontal portion 42 or 44 may rest in the bearing portion 28 of the bracket, but in the modification shown in FIGS. 2 and 3 it is the lower portion 44 that is to be positioned in the bearings 28. One reason for this is that the rotation of the rod is counterclockwise when viewed from the handle end, and means must be provided to prevent clockwise rotation of the rod. Thus in the bracket shown in FIG. 3, the handle is free to be rotated counterclockwise, but the portion 42 of the rod would bump against flange 26 if it were attempted to rotate the handle in a clockwise direction. It will be noted that if the rod were positioned with the upper portion 42 in the bearings 28, the handle could be rotated without restraint in either direction.

The purpose of making the bottom member 44 of the unit shown in FIGURES 1-3 the center of rotation thereof is so that the mass of the lever material above and below the center of rotation is approximately equal. Therefore when buff or draft shock loads occur of sufficient magnitude to cause rotation of the lever and possible lock set of coupler, the balancing of the mass above and below the center of rotation will remove the tendency of the lever to rotate under such shock conditions.

Should it be desired for any reason to have the upper portion 42 provide the axis of rotation for the handle, the bracket arrangement shown in FIGURES 5 and 6 would be used, wherein the upper portion 42 of the rod is positioned in the bracket to provide the axis of rotation. In this modification the rod may be rotated counterclockwise but not clockwise. It is appreciated that in this type of bracket the advantages of the mass distribution of the rod above and below the axis of rotation are forfeited.

The inner end of the rod 14 is provided with the usual hook portion 50 for hooking engagement with the rotor 52 of the coupler, which rotor is in turn connected to the lock lifter 54. Thus when the rod 14 is rotated counterclockwise, like motion will be imparted to the rotor which will lift the lock lifter to unlock the coupler. The other end of portion 14 is provided with an elongated eye 56 which surrounds the hairpin portions 42 and 44.

The eye is rather loose around the bars 42 and 44 so as to permit considerable angling of the eye as well as sliding of the eye on the bars. Obviously when the handle 40 is rotated, the rod that is in the bearings will be the axis of rotation and the other will act as a lever arm and correspondingly rotate the eye and rod 14. It should be noted that the eye 56 is formed by turning the rod 14 upwardly and then forming the elongated eye therein. The eye 56 is positioned on the hairpin portion by sliding same thereon over the bend 46 and then placing the hairpin portion in the bearings with the eye therebetween. It is thus seen that the application of the device to the car is very simple. The hook 50 is applied to the lock lifter, the eye 56 slid on the hairpin portion and the hairpin portion applied to the bearings. When therein, the parts cannot separate.

It is perfectly obvious that the eye 56 need not be elongated so as to surround both rods 42 and 44. It may be a simple eye surrounding rod 42 only with the depending portion in front of rod 44, and function equally as well.

Referring now to the modification shown in FIGURES 7-10 of the drawings, and more particularly to FIGURE 7, the uncoupling assembly is indicated generally by reference numeral 60 and includes a bracket 62 and a lever assembly having a first or handle section 64 and a second coupler actuating section 68 which is non-rotatably slidable with respect to the section 64 and terminates in a hook 70 for a purpose hereafter apparent. This slidability is necessary to compensate for the wide swing and long relative travel of the coupler, shown at 72, with respect to the car body, indicated at 74. In all modifications the distance the lever extends is determined by the angularity of mounting of the device in its bracket, the amount of travel of the sliding center sill and its cushioning arrangement, the length of the coupler shank, the degree of lateral swing of the coupler and the size of the striker opening.

The bracket 62 comprises a Z-shaped member which includes a flat substantially rectangular section 76, which is secured to and extends downwardly with respect to the end of the car body 74, a section 80 substantially perpendicular to the section 76 extending horizontally away from the car body and a flange 82 extending angularly downwardly with respect to the section 80 forming a downturned lip.

The portion 76 of the bracket is provided with spaced holes through which rivets 77 may extend and secure the bracket to the corner of the car. Adjacent one side of the portion 80 is provided a round hole indicated at 78 and adjacent the other side of said portion 80 there is provided an elongated hole indicated at 79. The lever guide comprises a round bar 81 formed into C-shape, in length about the width of the portion 80 of the bracket. The outer end of this lever guide is riveted to portion 80 through round hole 78 and the other end of the lever guide is bent at an angle as indicated at 83 and passed down through the elongated hole 79. This lever guide 81 thus forms a somewhat slightly elongated clevis for reception of the outer end of the uncoupling device. This bracket and lever guide are shown, described and claimed in Patent No. 2,839,204 owned by my assignee. A modified form of support bracket is shown in FIGURES 11 and 12, the only difference being that the portion 80' of the bracket is not quite as long, and upon the portion 80' of the bracket are secured the ends of a U-shaped clevis 84, which clevis extends outwardly beyond the flange 82' to be able to receive the outer end of the operating rod or lever.

The outer or handle section of the operating device comprises a downwardly extending grip portion 90 having an inwardly turned end 92 which is thus turned to avoid catching clothing of trainmen in operating the device to unlock the coupler. This handle section has a complete reverse bend 94 formed therein which surrounds the clevis 84 or 81 and thus makes slideable and pivotal connections thereto. The clevis is slid in this eye before

the ends of the clevis are bolted or riveted to the bracket 62 or 62'. The handle section is then turned laterally inwardly a substantial distance as shown at 66.

The lever section 68 comprises an elongated straight portion 100 terminating at its inner end in the hook 70 for attachment to the car coupler indicated at 72. The outer end of this rod portion 100 is bent back upon itself by a U-bend indicated at 104 forming a shorter portion 102 in spaced parallel relation to portion 100 and the end of which is bent at right angles thereto as at 106 into abutment with portion 100. The lever section 68 may be made in two pieces by providing a welded joint in the vicinity of the U-bend 104.

The lever section 68 is mounted for sliding movement with respect to the handle section 64 by means of a pair of spaced upwardly facing U-shaped clips 108—108. Clips 108 have parallel arms 110 and 112, which arms surround the portions 100 and 102 of the inner coupler operating section 68 and the free ends of the arms 110 and 112 are welded to the opposite sides of portion 66 of the handle section 64. Arms 110 and 112 are provided with registering openings through which bolts 114 extend between the lever sections 100 and 102. On these bolts, between arms 110 and 112 are anti-friction sleeves 116 upon which are mounted rollers 118 which roll between the members 100 and 102 and maintain the handle section 64 out of frictional contact with coupler operating section 68. The coupler operating section 68 is thus free to slidably and non-rotatably move relative to the handle section 64 and thus compensate for in-and-out and lateral movements of the coupler.

From the foregoing teaching those versed in this art will understand how the operating device functions. When it is desired to unlock the coupler, for example, the handle 40 or 90 is grasped by a trainman and pulled outwardly from the car so as to pivotally rotate in a counterclockwise direction with respect to its clevis 81 or 84. This rotation will cause the sections 64 and 68 to likewise move in an orbital path counterclockwise to thus rotate the rotor of the coupler.

There has thus been provided a coupler operating device assembly which accommodates couplers mounted in sliding center sills with cushion underframes, and which couplers move a total of up to 48" between extreme buff and extreme draft positions.

I claim:

1. In an uncoupling device for railway car couplers mounted in sliding center sills in cushioned underframes for longitudinal movements up to about 48" and lateral movements of 15°, a bracket mounted on the end of the car, a coupler operating device comprising a two-part lever, one part having elongated parallel rods connected by a U-bend, a handle depending from the end of one of said parallel rods, bearings on said bracket for rotatably receiving opposite ends of one of said parallel rods, said bracket preventing clockwise rotation of said rods, the other part of said lever having means at its inner end for attachment to the lock lifter of a car coupler for operation of said lock lifter upon anti-clockwise rotation of said lever, the outer end of said other part having an elongated eye slidably and non-rotatably encircling said rods between said bearings, the combined lengths of the parts being such that they may contract to about 38" and extend to about 72" whereby the eye may slide and angle on said parallel rods to compensate for said relative lateral and longitudinal movements of the car body and coupler, and be rotated thereby to operate the coupler.

2. A coupler operating lever arrangement for a railway car having a sliding center sill and cushioned underframe, a coupler mounted therein for longitudinal movements up to about 48" between extreme buff and extreme draft positions, and lateral movements up to 15° on either side of the center line, the combination with said car and coupler, of bearings mounted on the end of said car adjacent a side thereof, the mounting of said bearings being such

that they are axially alined, said axis diverging from the car end toward the car coupler and intersecting the coupler travel at approximately its midpoint, said operating lever comprising two parts, one part having a pair of elongated spaced parallel rods connected at one end by a U-bend, a handle outboard of the outer bearing depending from the other end of one of said rods, the other end of the other rod being secured to said handle, one of said parallel rods being mounted in said bearings and forming the axis of rotation of said handle portion, the other part of said lever having a hook at one end for attachment to the lock lifter of said coupler, and an eye at the other end of said part slidably and non-rotatably engaging the parallel rods, the other of said parallel rods acting as a lever to engage the other part and impart rotary motion thereto the combined lengths of said parts being such that they may contract to 38" and extend to about 72", whereby the eye may slide and angle with respect to said elongated rods to compensate for said lateral and longitudinal movements of said coupler and be rotated thereby to operate the coupler.

3. A coupler operating lever arrangement for a railway car having a sliding center sill and cushioned underframe with a wide swing and long travel coupler mounted therein for longitudinal movements of up to 48" and lateral movements of up to 15°, the combination with said car and coupler of a mounting bracket secured to one end of the car adjacent one side thereof, a horizontal flange issuing normally from said bracket outwardly from said end, bearings mounted on said flange, said bearings being axially alined on an axis which diverges from the car end toward the coupler, said operating lever comprising two parts, one part having elongated spaced parallel rods connected at one end by a U-bend, a handle depending from the other end of one of said rods, the other end of the other rod being secured to said handle thereby forming a flattened loop, one of said parallel rods being rotatably mounted in said bearings, the other part comprising a rod having means at its inner end for attachment to the lock lifter of a car coupler for operation of said lock lifter upon counterclockwise rotation of said rod, the outer end of said other part being offset and formed into an eye slidably and nonrotatably encircling said parallel rods between said bearings, the combined lengths of said parts being such that they may contract to about 38" and extend to about 72", whereby the eye may slide and angle on said parallel rods, moving progressively away from said end as the eye moves inwardly on said parallel rods to compensate for said lateral and longitudinal movements of the car body and coupler.

4. A coupler operating lever mounting arrangement for a railway car having a sliding center sill and cushioned underframe and a coupler mounted therein for longitudinal movements up to 48" and lateral movements up to 15°, the combination with said car and coupler of a relatively wide mounting bracket secured to one end of said car adjacent one side thereof, a horizontal flange extending from said bracket, spaced bearings supported by said flange on a common axis that diverges from the car end toward the coupler and intersects the coupler travel at approximately its midpoint, said operating lever comprising two parts, one part having a pair of axially rotatable elongated spaced parallel rods connected by a U-bend, a handle depending from one of said rods to rotate same, and the other end of the other of said rods being secured to the handle, one of said rods being supported in said bearings, the other part of said lever having a hook at its inner end engaging the lock lifter of said coupler to operate same upon rotation of said other part in one direction, the other end of said other part being turned substantially normal thereto and formed into an elongated eye slidably and non-rotatably encircling said parallel rods, the combined lengths of said parts being such that they may contract to about 38" and extend to about 72", whereby the eye may slide and angle on said rods to

compensate for the wide lateral and longitudinal movements of said coupler relative to the car body, and be rotated thereby to operate the coupler upon operation of said handle.

5. Apparatus for uncoupling a coupler of a railway car having a sliding center sill and cushioned underframe permitting longitudinal coupler movements up to 48" and lateral movements up to 15° comprising a bracket mounted on said car end adjacent one side thereof, a lever guide of substantially C-configuration mounted on said bracket and extending outwardly with respect thereto, and a lever assembly including a handle section and a lever section slidably mounted on said handle section, said handle section rotatably mounted on said lever guide and having a grip portion and a shank extending angularly with respect to the longitudinal axis of said grip portion, said lever section having a body portion, a U-bend and a second portion extending parallel to said body portion, a plurality of U-shaped clips secured to said handle section and slidably engaging said lever section for simultaneous rotational movement, said lever section terminating in a hook adapted to lift the lock lifter of the car coupler, said lever section being slidable with respect to said handle section, the combined length of said sections being such that they may contract to about 38" and extend to about 72" to accommodate the said relative movement between the car coupler and the car body.

6. Apparatus for uncoupling a coupler of a railway car, said coupler being mounted for longitudinal movements up to 48" and lateral movements up to 15°, said apparatus comprising a bracket having a substantially rectangular section adapted to be secured to the end of a car body at one side thereof, another section extending angularly with respect to the longitudinal axis and the transverse axis of said first section, a lever guide mounted on said other section and extending angularly with respect thereto and angularly with respect to the longitudinal axis and the transverse axis of said first section of said bracket, and a lever assembly including a handle section and a lever section slidably mounted on said handle section, said handle section mounted for rotation of said lever guide and having a grip portion and a shank extending angularly with respect to the longitudinal axis of said grip portion, said lever section having a body portion, a U-bend and a second portion extending parallel to said body portion, a plurality of U-shaped clips secured to said handle section and slidably engaging said lever section for simultaneous movement, said lever section terminating in a hook adapted to lift the lock lifter of the car coupler, said lever section being slidable with respect to said handle section, the combined lengths of said sections being such that they may contract to about 38" and extend to about 72" to accommodate the relative movement between the car coupler and the car body.

7. Apparatus for uncoupling a coupler for a railway car comprising a bracket having a substantially rectangular section adapted to be secured to the end of a car body at one side thereof, another section extending angularly with respect to the longitudinal axis and the transverse axis of said first section, said coupler being mounted for longitudinal movements of up to about 48" and lateral movements of up to 15°, a lever guide mounted on said other section and extending angularly with respect thereto and angularly with respect to the longitudinal axis and the transverse axis of said first section of said bracket, and a lever assembly including a handle section and a lever section slidably mounted on said handle section, said handle section mounted for rotation on said lever guide and having a grip portion and a shank extending angularly with respect to the longitudinal axis of said first section of said bracket, said shank being movable in an orbital path upon actuation of said grip portion, said lever section having a body portion, a U-bend and a second

portion extending parallel to said body portion, a plurality of U-shaped clips secured to said handle section and slidably engaging said lever section for simultaneous movement, said lever section terminating in a hook adapted to lift the lock lifter of the car coupler, said lever section being slidable with respect to said handle section, the combined lengths of said sections being such that they may contract to about 38" and extend to about 72" to accommodate the relative movement between the car coupler and the car body.

8. The combination with a railway car having a sliding center sill and cushioned underframe with a wide swing and long travel coupler mounted therein for longitudinal movements of up to 48" and lateral movements up to 15°, of a device for operating said coupler from the side of the car, said device comprising a handle section and a coupler operating section, means rotatably supporting said handle section on the end of said car adjacent one side thereof, a handle depending from said handle section outboard of said means, said coupler operating section having a hook at one end for attachment to the coupler for operation thereof upon rotation of said device, the handle section including a pair of elongated spaced parallel rods one of which is mounted in said means and the other of said sections overlapping and provided with offset means for sliding non-rotative engagement with said parallel rods, the combined lengths of said sections being such that they may contract to about 38" and extend to about 72" to accommodate said relative movements between the car coupler and car body.

9. An uncoupling lever for operating railway car couplers mounted for longitudinal movements of up to 48" and lateral movements of up to 15°, comprising a two-part lever, one part having a pair of elongated spaced parallel rods connected at one end by a U-bend, a handle depending from the other end of one of said rods, the other end of the other of said rods abutting and being secured to said handle, the other part of said lever comprising a rod having a hook at one end for attachment to the lock lifter of a car coupler, the other end of said other part being formed into an offset eye slidably and non-rotatably engaging the said parallel rods, whereby said eye may slide and angle on said rods, the combined lengths of said parts being such that they may contract to about 38" and extend to about 72" to compensate for said relative lateral and longitudinal movements of said car body and coupler, one of said rods of the handle portion acting as the axis of rotation thereof when said handle is operated and the other of said rods acting as a lever to cause the other part to orbit around said axis of rotation and operate the coupler.

10. An uncoupling lever for operating the lock lifter of railway car couplers mounted for longitudinal movements of up to 48" and lateral movements of up to 15°, comprising in combination a two-part lever, one part having a pair of spaced elongated rods connected together at one end, a handle depending from the other end of one of said rods for rotating said one part on the axis of one of said rods, the other end of the other of said rods abutting said handle and being secured thereto, means on the end of said car for supporting one of said rods for rotation on its axis while the other rod orbits around said axis, said axis diverging from said car end toward said coupler, the other part of said lever comprising a rod having a hook at one end for attachment to the lock lifter of a car coupler, the other end of said part being formed into an offset eye slidably and non-rotatably engaging said parallel rods whereby said eye may slide and angle in relation to said rods, and be rotated thereby to operate the coupler, the one of said parallel rods supported in said means being the axis of rotation of said pair of rods while the other of said rods acts as a lever to cause said other part of said lever to orbit around said axis of rotation and actuate the coupler, the com-

combined lengths of said parts being such that they may contract to about 38" and extend to about 72".
